UNITED STATES PATENT OFFICE.

D'ORSAY McCALL WHITE AND LYLE K. SNELL, OF DETROIT, MICHIGAN, ASSIGNEES TO CADILLAC MOTOR CAR COMPANY, OF DETROIT, MICHIGAN, A CORPORATION OF MICHIGAN.

HYDROCARBON-MOTOR.

1,321,172.

Specification of Letters Patent. Patented Nov. 11, 1919.

Application filed November 8, 1915. Serial No. 60,210.

To all whom it may concern:

Be it known that we, D'ORSAY McCALL WHITE, a loyal subject of the King of England, and LYLE K. SNELL, a citizen of the 5 United States, both residents of Detroit, Wayne county, State of Michigan, have invented certain new and useful Improvements in Hydrocarbon-Motors, of which the following is a specification.

10 This invention relates to hydrocarbon motors, and particularly cooling systems therefor.

With the increased number of cylinders used in a modern high speed internal combustion engine, particularly the water cooled type, considerable difficulty has been encountered in efforts to provide simple and efficient means for maintaining the cooling medium at a proper uniform temperature in 20 the various cylinder blocks.

In previous cooling systems, where a single path circulation is used for cooling a multicylinder motor, it is frequently found that when the temperature is maintained 25 sufficiently high in the cylinders adjacent the inlet to the water jackets, the temperature in the jackets of the cylinders remote from the inlet becomes dangerously high, and in order to maintain the temperature 30 of the cooling medium in the jackets of the cylinders remote from the water inlet below the desired maximum, the temperature of the cylinders adjacent the inlet must be kept too low for efficient operation; therefore, one of 35 the salient objects of this invention is to improve the arrangement and disposition of the parts, and to materially increase the efficiency of cooling systems, particularly adapted for use with hydro-carbon motors, 40 of the multi-cylinder type.

Another object is an arrangement of circulating paths which will minimize the difference in temperature of the cooling medium in the various cylinder blocks of a 45 multi-cylinder motor.

Another object is to provide a cooling system which will maintain all of the cylinders at a substantially uniform temperature.

Another object is to decrease the length 50 of the paths of circulation of the cooling medium and at the same time improve the general efficiency of the system.

Another object is to provide each of sev-

eral water cooled cylinder blocks with an independent circulating cooling system, 55 which may use a common radiator.

Another object is to provide an internal combustion engine comprising a plurality of cylinder blocks, with improved means for independently circulating the cooling medium, 60 as by parallel paths, through the jackets of the various cylinder blocks.

Other objects will appear from the following description taken in connection with the drawings which form a part of this 65 specification, and in which:

Figure 1 is a side elevation of a power plant of a hydrocarbon motor, comprising an embodiment of this invention;

Fig. 2 is a front elevation of the power 70 plant illustrated in Fig. 1, with the radiator removed and showing certain portions broken away;

Fig. 3 is a horizontal section, substantially on the line 3—3 of a regulator shown 75 in Fig. 2.

Fig. 4 is a vertical section substantially on the line 4—4 of the same regulator and pump mechanism, shown in Fig. 2; and

Fig. 5 is a rear elevation of the upper 80 part of the radiator shown in Fig. 1.

Referring to the drawings, 10 represents a crank case; 11 and 12 a plurality of cylinder blocks mounted thereon, in any suitable manner, in V relation. Each of the 85 cylinders are provided with the usual valve mechanism 13 operated by means of rocker arms 14 and a cam shaft 15, which may be driven by gearing not shown, from the crank shaft 17. The crank shaft is adapted to be driven by means of pistons 18, which are connected to the crank shaft 17 by connecting rods 19, and piston pin 20 and crank pin 21.

A shaft 22, arranged transversely to the crank shaft 17 and adapted to be driven therefrom, through the gears 23 and 24, is shown as mounted in suitable bearings 25, arranged in the crank case 10. This shaft is adapted to drive a plurality of pump 95 mechanisms arranged at each end thereof, and which will be more particularly described hereinafter.

Each of the cylinder blocks 11 and 12 is also provided with an independent cooling 100 means, comprising water jackets 26, having 105

an intake port 27 arranged adjacent one end of the cylinder block. An outlet port 28 may be provided adjacent the end of the cylinder block remote from the intake port 27. This outlet port 28 may then be connected, as shown, by means of a conduit 29 and a common return 30, which is attached at 31 in any well known manner, to a common cooling means or radiator 32 for both of the cylinder blocks. Arranged adjacent to each side of the lower portion of a radiator 32 are ports 33, each of which has suitable connections, as by conduit 34 and conduit 35 with the intake port 27 for the jackets of the respective cylinder blocks.

While a pump mechanism and thermostat control, indicated at 36, and which will be more particularly described hereinafter, is shown as arranged between the conduits 34 and 35, it is not essential that such mechanism and thermostat be included in this system as it will be seen, this invention is as applicable to thermo siphon systems.

We have also provided a connection or bypass 37, communicating with the conduit 29 and adapted to be connected with the conduit 35, so that the circulating medium may flow through each of the cylinder blocks 11 and 12 independently of each other, and independent of the common return 30 and common cooling means 32, as will more particularly appear from the description of the operation of preferred forms of the system, as hereinafter set forth.

Pump mechanisms 36 and thermostat control, above referred to briefly, which may be provided for a force feed circulating system, comprise a two part casing 37' and 37'', suitably connected, as by bolts 38, to opposite sides of the crank case 10. Suitably arranged in bearings in said casing 37' are two pump shafts 39, each having a pump impeller 40, suitably secured thereto, as by a pin 41, this shaft 39 being preferably detachably connected, as at 42, to an end of the transversely arranged driving shaft 22 hereinbefore described. Suitably secured to the top of the casing 37'', as by bolts 43, is a cover or valve chamber, provided with an inlet port 45, adapted to be connected with the conduit 34. The port 45 communicates with an inner shell 46, shown as formed integral with the chamber 44 and provided with ports 47 and 47', adapted to be controlled by a valve mechanism, which will be more particularly described hereinafter.

It will be seen that the chamber 44 is provided with a plate 48, suitably secured thereto, as by bolts 49 and provided with a port 50 and nipple 51 communicating therewith, the nipple having the bypass 37 suitably thereto. Arranged in the boss 52 formed in the casing 37'', is an adjustable member 53, to which is secured as by a threaded connection, an automatic control in the form of a

thermostat member 54, to which is secured upper and lower valve members 55 and 56 respectively, which form a balanced valve for controlling the flow of cooling medium from the port 45 to the inside 57 of the pump casing, the upper valve, it will be seen, being adapted to restrict the flow of cooling medium through the port 50 when the ports at 47 and 47' are opened.

Arranged between the cylinder blocks 11 and 12 is a gas inlet 58, which is secured as by bolts 59 to said blocks. A carbureter 60 is shown as connected to said gas inlet. The inlet 58 is also shown as provided with a water jacket 61, having a plurality of inlet ports 62, each of which is shown as connected as by conduits 63 to the upper part 64 of the cylinder jacket of one of the cylinder blocks. The water jacket 61 is also provided with a plurality of outlet ports 65, each of which is shown as connected by conduits 66 to a port 67, formed in the cover 48.

It will also be understood that the valve member 55 may be provided with a notch 68 formed therein, adapted to permit a circulation of water through the jacket 61, even though the port 50 is restricted by the valve member 51.

It will be seen from the above description that we have provided a cooling system 95 adapted for use in a hydrocarbon motor, comprising a plurality of cylinder blocks, each of which has independent circulating paths, as well as independent means for supplying cooling medium to its circulating 100 system.

The operation of the cooling system for each of the blocks is as follows:

Assuming the motor to be started when the cooling medium is below the desired 105 temperature, the thermostat 54 will close off at 47 and 47' the communication of the port 45 with the inside 57 of the chamber 37', 37'', and the cooling medium will be drawn in the pump at 69, discharging it therefrom through the conduit 35 to the cylinder jacket at 27 and thence into the conduit 29, and, as the radiator 32 is cut off from the pump chamber, the cooling medium will be bypassed through the conduit 37 to the chamber 57 and then returned, as described. Thus it will be seen, that with the thermostat in this position the cooling medium circulates through each of the blocks independent of the other.

However, when the temperature of the cooling medium rises above a predetermined height, the thermostat 54 raises the valve members 55 and 56 and restricts the flow of water through the port 50 to the chamber 125 and the cooling medium will circulate from the pump, through the same circuit as when the communication with the port 45 is cut off, until the water flows to the conduit 29, where it will continue to flow to the com- 130

mon return 30 and radiator 32. With the valve in this position, it will be seen that a parallel circulating system is provided through each of the cylinder blocks, with a means in the form of a common radiator or common return, for equalizing the temperature in the various blocks.

It will also be understood that there is a continual thermo siphon circulation through the jacket 61 of the intake 58 regardless of the position of the thermo controlled valve, as the notch or port 68 formed in the valve member 55 permits a restricted flow of water therethrough.

By providing parallel independent circulation paths for the various cylinder blocks, as described and illustrated, it will be seen that we have clearly minimized, by shortening the paths of circulation, the difference in temperature of the cooling medium in the various cylinder blocks, and have rendered the temperature substantially uniform, while at the same time providing a very simple and compact arrangement of parts.

It will be understood that while we have shown two separate pump mechanisms, each provided with its own thermostat, it is obvious to one skilled in the art that the two pump mechanisms may be grouped into one and controlled by a single thermostat.

While we have shown and described a preferred form of our invention, it will, of course, be obvious to one skilled in the art, that various modifications may be made without departing from the spirit or scope of our invention, which will be covered by the claims.

Having thus described our invention, what we claim and desire to secure by Letters Patent is:—

1. In a hydrocarbon motor, in combination, a plurality of water jacketed cylinder blocks, and independent means for circulating water to each of said blocks.

2. In a hydrocarbon motor, in combination, a plurality of water jacketed cylinder blocks, and independent means for circulating water to each of said blocks, and returning it thereto.

3. In a hydrocarbon motor, in combination, a plurality of water jacketed cylinder blocks, independent means for circulating water through said blocks, and a common return to said independent means.

4. In a hydrocarbon motor, in combination, a plurality of water jacketed cylinder blocks, independent means for supplying water to each of said blocks, a radiator, connections between said blocks and said radiator, and independent means connecting said radiator with said supply means.

5. In a hydrocarbon motor, in combination, a plurality of water jacketed cylinder blocks, independent mechanism for circulating water through each of said blocks, a

common return for said water, and means for controlling the circulation of the water.

6. In a hydrocarbon motor, a plurality of water jacketed cylinder blocks, independent pump mechanisms for circulating water through each of said blocks, a common return for said water, and means arranged between said return and said circulating mechanisms for controlling the circulation of the water.

7. In a hydrocarbon motor, a plurality of cylinders, cooling jackets therefor, independent means for feeding the cooling medium to each of said jackets, a common return from said jackets to said feeding means, and thermostatically controlled means between said return and said feeding means.

8. In a hydrocarbon motor, in combination a plurality of cylinders, cooling jackets therefor, independent means for circulating cooling medium to each of the jackets, a common return for said circulating means, a separate return from each of said jackets to said feeding means, and means controlling the circulation through the various returns.

9. In a hydrocarbon motor, in combination a plurality of cylinders, cooling jackets therefor, independent means for circulating cooling medium to each of the jackets, a common return for said circulating means, bypasses around said common return, from each of said jackets to said feeding means, and automatic means controlling the circulation through the various returns.

10. In a hydrocarbon motor, in combination a plurality of cylinders, cooling jackets therefor, independent means for circulating cooling medium to each of the jackets, a common return for said circulating means, separate bypasses around said radiator for each of said jackets, and means controlling the circulation through said bypasses.

11. In a hydrocarbon motor, in combination, a plurality of water jacketed cylinder blocks, independent means for circulating water through each of said blocks, comprising a plurality of pump impellers, each of said impellers feeding water to one block only.

12. In a hydrocarbon motor, in combination a plurality of water jacketed cylinder blocks, independent means for supplying water to each of said blocks, a cooling means, independent means connecting each of said blocks with said cooling means, and connections between said cooling means and said first means.

13. In a hydrocarbon motor, in combination, a plurality of water jacketed cylinder blocks, independent means for circulating water through said blocks, a common radiator connected with said jackets, means connecting said radiator with said independent

circulating means, bypass returns connecting said cylinder blocks with said circulating means, and means for controlling the circulation through the radiator and bypass 5 returns.

14. In a hydrocarbon motor, the combination with a plurality of water jacketed cylinder blocks, of a plurality of pump mechanisms, each adapted to feed water to one of 10 said jackets independently of the other, and means for returning water to said pump mechanisms.

15. In a hydrocarbon motor, the combination with a plurality of water jacketed cylinder blocks, of a plurality of pump mechanisms, each adapted to feed water to one of 15 said jackets independently of the other, a common radiator for said cylinder blocks, and connections from said radiator to said 20 pump mechanisms.

16. In a hydrocarbon motor, the combination with a plurality of water jacketed cylinder blocks, of a plurality of pump mechanisms, each adapted to feed water to one of 25 said jackets independently of the other, independent returns from each of said jackets to their respective pump mechanisms, and a common radiator for said jackets.

17. In a hydrocarbon motor, the combination 30 with a plurality of water jacketed cylinder blocks, each jacket having an inlet port, and an outlet port, and independent connections between each of said inlet ports and their respective outlet ports.

35 18. In a hydrocarbon motor, the combination with a plurality of water jacketed cylinder blocks, each jacket having an inlet port and an outlet port, a radiator having a single inlet port and a plurality of outlet ports, 40 connections between said outlet ports of said jackets and said radiator inlet port, and independent connections between each of said radiator outlet ports and each of said jacket inlet ports.

45 19. In a hydrocarbon motor, the combination with a plurality of water jacketed cylinder blocks, each jacket having an inlet port and an outlet port, a radiator furnished with a port having a common connection with one 50 of the ports of each of said blocks, said radiator also having a plurality of ports each

having independent connections with the other ports of each of the blocks.

20. In a hydrocarbon motor, the combination with a crank case, and a plurality of 55 water jacketed cylinder blocks mounted thereon in V relation, of a plurality of pump mechanisms mounted on said crank case and adapted to supply water to each of said jackets. 60

21. In a hydrocarbon motor, the combination with a crank case, and a plurality of water jacketed cylinder blocks mounted thereon in V relation, of a plurality of pump mechanisms mounted on opposite sides of 65 said crank case and adapted to independently supply water to each of said jackets.

22. In a hydrocarbon motor, the combination with a crank case, and a plurality of water jacketed cylinder blocks mounted 70 thereon in V relation, of a plurality of pump mechanisms mounted on opposite sides of said crank case, connections between each of said pumps and a lower portion of each of said jackets adapted to supply water thereto, and a common return from the upper portion of said jackets to said pumps. 75

23. In a hydrocarbon motor, the combination with a crank case, and a plurality of water jacketed cylinder blocks mounted 80 thereon in V relation, of a plurality of pump mechanisms mounted on opposite sides of said crank case, connections between each of said pumps and a lower portion of each of said jackets adapted to supply water thereto, 85 independent and common returns between the upper part of each of said jackets and said pump mechanisms.

24. In a hydrocarbon motor, the combination with a plurality of water jacketed cylinder blocks, of means for supplying water thereto comprising independent pump mechanisms for each of said blocks, and means for driving said pump mechanisms from a single shaft. 90

In testimony whereof, we affix our signatures in the presence of two witnesses.

D. McCALL WHITE.
